United States Patent Office

Des. 190,143
Patented Apr. 18, 1961

190,143

DISPLAY BOX

Lewis Douglas Young, 13 Laurel St., Providence, R.I.

Filed Sept. 16, 1957, Ser. No. 47,756

Term of patent 14 years

(Cl. D58—12)

Fig. 2.

Fig. 1 is a perspective view of a display box showing my new design; and

Fig. 2 is a side elevation thereof.

The rear and hidden side of the box are substantially like the front and side shown respectively.

I claim:

The ornamental design for a display box, substantially as shown and described.
